US00D616472S

(12) **United States Design Patent**
Fusejima

(10) **Patent No.:** **US D616,472 S**
(45) **Date of Patent:** **** May 25, 2010**

(54) **POWDER AND PARTICLE COATING APPARATUS**

(75) Inventor: **Yasutoyo Fusejima**, Tokyo (JP)

(73) Assignee: **Freund Corporation**, Tokyo (JP)

(**) Term: **14 Years**

(21) Appl. No.: **29/311,548**

(22) Filed: **Apr. 20, 2009**

(30) **Foreign Application Priority Data**

Oct. 20, 2008 (JP) 2008-026872

(51) **LOC (9) Cl.** **15-09**

(52) **U.S. Cl.** **D15/122**

(58) **Field of Classification Search** D15/122,
D15/124, 199; 118/64, 300, 309, 310, 324

See application file for complete search history.

(57) **CLAIM**

The ornamental design for a powder and particle coating apparatus, as shown and described.

DESCRIPTION

FIG. 1 is a front elevation view of a powder and particle coating apparatus.

FIG. 2 is a rear elevation view of a powder and particle coating apparatus of FIG. 1.

FIG. 3 is a left side view of a powder and particle coating apparatus of FIG. 1.

FIG. 4 is a right side view of a powder and particle coating apparatus of FIG. 1.

FIG. 5 is a top view of a powder and particle coating apparatus of FIG. 1.

FIG. 6 is a bottom view of a powder and particle coating apparatus of FIG. 1; and,

FIG. 7 is a perspective view of a powder and particle coating apparatus of FIG. 1.

The broken lines in the drawings depict unclaimed environmental subject matter.
